UNITED STATES PATENT OFFICE.

LAWRENCE H. JENSEN, OF ST. CHARLES, ILLINOIS.

SPARK-PLUG AND SPARKING CIRCUIT.

1,191,429.

Specification of Letters Patent. Patented July 18, 1916.

Application filed December 26, 1914. Serial No. 879,003.

To all whom it may concern:

Be it known that I, LAWRENCE H. JENSEN, a citizen of the United States, and a resident of St. Charles, in the county of Kane and State of Illinois, have invented certain new and useful Improvements in Spark-Plugs and Sparking Circuits, of which the following is a specification.

My present invention relates to improvements in spark plugs and sparking circuits and has special reference to that variety of spark plugs or sparking circuits in which are provided a plurality of spark gaps, across which the current must jump in order to produce the spark and the object of my invention is to increase the intensity of the spark.

I attain the above object by means of the structure illustrated in the accompanying drawings in which:

Figure 1 is a plan of the end of the spark plug upon which the sparks are produced. Fig. 2 is a vertical section on the line 22 of Fig. 1; and Fig. 3 is a schematic view more clearly showing the arrangement of circuit.

Similar reference characters refer to similar parts throughout these several views.

The spark plug comprises the usual body portion, 4, made preferably in a hexagonal form so as to readily take a wrench. The body portion, 4, has a reduced and exteriorly threaded end, 5, adapted to screw into the wall of the combustion chamber. The body portion, 4, and reduced end, 5, are centrally bored to receive the insulating core, and the central bore is flared in the body portion at 6, and at the upper end of the flare the central bore is enlarged and interiorly threaded, at 8, to receive the retaining nut, 9, which is also centrally bored for the passage of the insulating core, 10. The inner end, 7, of the core, 10, is preferably made cylindrical to pass through the central bore in the reduced end, 5, of the body portion, and above the cylindrical portion, 7, it is given a conical form, at 11, to fit within the flared portion, 6, of the body portion, and above the conical portion, 11, it is provided with an annular shoulder, 12, which fits within the enlarged portion, 8, of the bore in the body portion, and upon the upper end of the annular shoulder, 12, abuts the lower end of the retaining nut, 9. Above the annular shoulder, 12, the core is preferably made cylindrical so as to extend

through and above the central bore of the retaining nut, 9.

The insulating core, 10, is made of porcelain, mica, lava, or any material which will stand a considerable degree of heat and retain its insulating properties. In the insulating core, 10, are provided a plurality, preferably four, longitudinal channels, 13, 14, 15, and 16 for the reception of the conductors comprising the sparking circuit, 65 and at the outer end of the core are two radially and transversely disposed channels, 17 and 18 leading into and communicating with respectively two of the longitudinal channels, in this instance, channels 13 and 15. 70

The wiring of the core is accomplished by inserting pieces of conductors, of suitable size and length into the longitudinal channels. The upper or inclosed end of the piece of conductor which occupies the channel, 13, 75 is twisted back upon itself to provide a loop, 19, which engages a hook, 20, upon the end of a rod, 21, extending through the channel, 17. The outer end of the rod 21 is threaded and is held in place by a retaining nut, 22, 80 and an outer or cap nut, 23, is provided between the inner end of which and the retaining nut, 22, is held the conductor, 24, leading to the source of supply of the high potential or sparking circuit. 85

The end, 25, of the piece of conductor occupying longitudinal channel, 13, extends from the inner end of the core and is bent to extend toward the conductor extending from the next or nearest channel, 14. The 90 conductors occupying the channels 14, 15 and 16, are preferably pieces of wire of suitable metal bent upon themselves so that there will be two ends extending from the opening of each channel upon the inner end 95 of the core, which ends may be bent respectively toward the channels on either side. The pieces of conductor occupying channels, 14 and 16, may extend into their respective channels only sufficiently far to 100 secure them substantially, but the conductor occupying the channel, 15, or the channel which connects with the radial channel, 18, should extend sufficiently far back to engage a hook, 20^a, upon a rod, 21^a, disposed in said 105 channel, 18, and secured in position by a retaining nut, 22^a. To the rod, 21^a is secured by a cap nut, 23^a, a length of conductor, 26, forming an open circuit extending into the air and not connected in circuit with either 110

the high potential circuit, or the primary circuit, if a battery and coil instead of a magneto is employed in providing the sparking circuit with energy. One end of the conductor extending from the channel, 16, is extended toward a piece of conductor, 27, secured to and extending from the metallic body portion, 5, of the plug, which grounds or completes the high potential or sparking circuit through the metal of the motor.

A schematic view of the wiring is shown in Fig. 3. In this view I have illustrated a battery A and coil B as a source of supply for the high potential circuit C; but a magneto may be employed without departing from the spirit of my invention. The high potential circuit C is interrupted to provide spark gaps D, E, F, and G and to a portion of the circuit intermediate the gaps, preferably the central portion of such circuit is connected a length of open circuit H.

I have found that the addition of this length of open circuit connected to a portion of the high potential or sparking circuit, as above described, and running into the air adds very sensibly to the intensity of the sparks produced across the spark gaps.

Having described my invention what I claim as new and desire to secure by Letters Patent is:—

1. In a spark plug, a plurality of spaced conductors comprising a portion of a circuit having a plurality of interruptions or spark gaps, and means for connecting one of the intermediate spaced conductors with a length of conductor that is unconnected with the remaining portion of said circuit.

2. In a spark plug, a plurality of spaced conductors comprising a portion of a circuit having a plurality of interruptions or spark gaps, and a conductor connected with one of

the intermediate spaced conductors and unconnected with the remaining portion of said circuit.

3. In a spark plug, a plurality of spaced conductors comprising a portion of a circuit having a plurality of interruptions or spark gaps, and a conductor connected with one of the intermediate spaced conductors and terminating in the atmosphere.

4. In a spark plug, a circuit having a plurality of interruptions forming a plurality of sparking points and means for connecting an intermediate portion of said circuit with a conductor terminating in the atmosphere.

5. In a spark plug, a circuit having a plurality of interruptions forming a plurality of sparking points and a conductor connected to an intermediate portion of said circuit and terminating in the atmosphere.

6. A spark plug comprising a body portion, an insulating core mounted within said body portion, a plurality of longitudinal channels within said insulating core, conductors mounted within said longitudinal channels so as to project from one end thereof, one or more of said conductors having branched projecting ends, said conductors comprising with said body portion a portion of a circuit having a plurality of interruptions therein, and means for connecting an intermediate portion of said interrupted circuit with a length of conductor that is unconnected with the remaining portion of said circuit.

In testimony whereof I have hereunto set my name in the presence of two witnesses.

LAWRENCE H. JENSEN.
